UNITED STATES PATENT OFFICE

LEONARD C. ROBINSON, OF CHICAGO, ILLINOIS

SHOE CLEANING AND POLISHING MACHINE

Application filed August 28, 1925. Serial No. 53,143.

This invention relates to improvements in shoe cleaning and polishing machines and its object is to provide a machine of this class that is of durable construction, efficient and economical in operation.

With the foregoing and other objects in view the invention consists in the combination and arrangement of parts to be hereinafter fully described, pointed out in the appended claim and illustrated in the accompanying drawings which form a part of this application and in which—

Fig. 1 is a longitudinal sectional view through the machine and is taken on line 1—1 of Fig. 2.

Fig. 2 is a top plan view of the machine, the dust pan being omitted.

Fig. 3 is an enlarged sectional detail view showing the belt and pulley drive arrangement. Fig. 4 is a vertical sectional view showing the actuating mechanism for the polish applying means.

Fig. 5 is a cross section on line 5—5 of Fig. 2 showing the polishing brush support mechanism.

Figs. 6 and 7 are sections taken, respectively, on lines 6—6 and 7—7 of Fig. 5, enlarged.

Fig. 8 is a detail of a coil spring pulley belt employed.

Fig. 9 is a sectional detail view showing the dust receiving pan with support and control means therefor.

Fig. 10 is a vertical sectional view through the polish reservoir.

Like reference characters denote corresponding parts throughout the several views.

The machine comprises a frame of oblong shape and having the base 1 upon which are disposed the side walls 2, 3 and end walls 4, 5, a transverse partition 6 being arranged upon said base divides the frame into two compartments, one upon each side of said partition. A platform 7 formed with a perforation 7a receives a circular perforate plate 8 supported upon a cleat 9 carried by the platform and forms a cover for this compartment, the other compartment being open at the top.

Upon the base 1 at about the center of the compartment 5, 6 is a stationary sleeve 10

and slidably encompassing the same is the sleeve 11 formed with oppositely disposed slots 12 and terminating at its upper end in the flared race 13 provided with ball bearings 14 that support the grooved base 15 of the brush 16. A cord 17 extends through the slots 12 in the sliding sleeve and through perforations in the stationary sleeve and has its ends secured to said sliding sleeve at points diametrically opposite each other, said cord also passing through a perforation in a plunger 18 that extends through the platform 7, through the base of the brush and into the sleeve 10.

A belt 19 engages the grooved portion of the base 15 of the brush and passes over a pulley 20 supported by a bearing 21 carried in the frame compartment, said pulley 20 being operatively connected by the shaft 22 with a pulley 23 supported by the bracket 24. A belt 25 connects the pulley 23 with either a pulley 26 fast upon the drive shaft 27 or with a pulley 28 loose upon said shaft which shaft is driven by the motor 29. A belt 30 connects either the loose pulley 28 or the pulley 31 fast upon the drive shaft 27 with a pulley 32 fast upon the brush shaft 33 that is connected to another and similar brush shaft 34 by a crossed coil spring belt 35 that runs over the pulleys 36 one of which is fast upon each of the said brush shafts.

Each end of each brush shaft is mounted in a roller carriage 37 and said carriages are adapted to ride back and forth in the recesses 38 formed in the wall 4 and in the partition 6, each carriage being connected by a return spring 39 to a hook 40 at one end of the said recess, each carriage being connected also by a cord 41 that passes over a pulley 42, in said recess, through one of the vertical recesses 43 in said wall and partition to another carriage 44 operative in an enlarged portion 45 of the vertical recess 43, the carriages 44, two in number, being connected by a bridge bar 46, the ends of which are tubular to receive the outer ends of said carriages which bear against expansion coil springs 47 disposed in said tubular bridge ends.

The bridge bar is formed with a perforation 48 to permit passage therethrough of an

inclined tubular post 49 secured at its inner end to the base 1 and terminating at its upper end in a shoe plate 50. A plunger 51 provided at its outer end with a shoe plate 52 is disposed in the post 49 and is engaged by a pin 53 carried by the bridge bar 46 and passing through a slot 54 in the post. The position of the post 49 is between the brush shafts 33, 34 so that the plunger 51 and shoe plate 52 will be disposed between the brushes 55, two in number, carried by said brush shafts.

A circular dust pan 56 is formed with an arcuate slot 57 through which the sleeve 11 extends to secure said pan movably to the base 1, said pan being provided with a handle 58 fulcrumed upon the pin 59 to the base whereby said pan may be moved into and out of position beneath the brush 16. In the position beneath the brush it receives dirt falling therefrom and in its outer position the said dirt may be removed, swept out or otherwise disposed of. The pan is movable through a slot or cut out portion 60 in the wall 2 to provide clearance.

An angular bracket 61 secured to the side wall 3 of the frame carries a reservoir 62, at its upper end, for liquid shoe polish which polish is introduced through the orifice 63 and which is ejected through a valved orifice 64 opened by depressing the valve stem 65, the spring 66 serving to yieldingly retain said orifice closed. A rotary brush 67 is arranged beneath the reservoir 62 upon a brush shaft 68 journaled in said bracket 61 and in a bearing 69 and provided with a pulley 70 connected by belt 71, that passes through a perforation 72 in said wall 3, to a pulley 74 fast upon the drive shaft 27.

This machine may be placed upon the porch or in the reception hall of a dwelling or installed in shoe shining parlors. In use the party whose shoes are to be cleaned and polished turns on the motor 29 and shifts the belts 25, 30 to the pulleys 26, 23 thus driving the rotary brush 16. He now places one foot upon the plunger 18 which raises the said brush and the same rotating against the shoe cleanses it of dirt which falls into the pan 56 from which it may be removed as previously described. When one shoe is thus cleaned he repeats the operation upon the other shoe. He now shifts the belts 25, 30 back to the pulleys 23, 31 thus stopping rotation of the brush 16 and starting up the brushes 55. Previous to this, however, he depresses the plunger 65 causing polish to be applied to the brush 67 and so positions one shoe at a time that the said brush will apply thereto the polish.

He now places one shoe upon the foot plate 52 depressing the same together with the bridge 46 which draws the brushes 55 toward each other and causes them to rotate against the shoe, the brushes rotating toward each other due to the crossed belt 35 that rotates

the shafts 33, 34. When the shoe is removed from the foot plate it will rise again due to the action of the springs 39 and 47 and after both shoes are thus polished the motor is shut off thus stopping the mechanism.

What is claimed is:

In a shoe cleaning machine, a perforated housing, a rotary brush mounted for movement into and out of the perforation in said housing, a stationary sleeve upon the base of said housing having perforations near its top, a movable sleeve encompassing said stationary sleeve and directly supporting said brush, a plunger within said sleeves and projecting above the perforated portion of the housing, and a cord passing through said perforations and connecting the lower ends of said plunger and movable sleeve to raise the brush upon depression of the plunger.

In testimony that I claim the foregoing as my own I have hereto affixed my signature.

LEONARD C. ROBINSON.
